UNITED STATES PATENT OFFICE.

JAMES W. JOHNSTON, OF CHICAGO, ILLINOIS.

SCHOOL-DESK.

SPECIFICATION forming part of Letters Patent No. 784,050, dated March 7, 1905.

Application filed May 4, 1903. Serial No. 155,581.

To all whom it may concern:

Be it known that I, JAMES W. JOHNSTON, a citizen of the United States, residing at Chicago, in the county of Cook and State of Illinois, have invented certain new and useful Improvements in School-Desks, which are fully set forth in the following specification, reference being had to the accompanying drawings, forming a part hereof, and in

10 which—

Figure 1 shows said new school-desk in end elevation. Fig. 2 shows a face view of the base or floor member as seen when looking toward either the seat or from its rear, the bracket being cut away by a plane parallel to the slot-face. Fig. 3 shows the top of the desk-bracket and the desk-braces below the plane 3 3 of Fig. 1. Fig. 4 shows the metal parts of the desk as seen from the desk-front 15 side with a fragment of the desk on it. Fig. 5 shows the desk on the seat-front side with the seat and back and the metal back-supporting mechanism behind the back shown in broken outlines.

20 The object of this said invention is to improve the details of construction and operation of school-desks of the class herein shown and described. To attain said desirable ends, said new device is constructed in substantially the following manner, namely:

The base or foundation piece A is now made as a single solid casting, provided with necessary adjuncts and parts modified and adapted to this present structure. Formerly said base was in two distinct parts, which were connected at their tops by raised short corrugated surfaces coupled by a bolt. Each leg of this foundation-piece A is provided with a longitudinal slot a a, whereof the length may range from five to ten inches, more or less, according to the degree of adjustment desired. The angle of the legs a from the vertical is about twenty-three degrees, and they are connected by a web and arch into one piece, substantially as shown. The feet a' of said legs have plain front and rear edges and rounded ends, through which at each end is passed a screw a². The outer faces b of said slots extend in both directions 25 longitudinally, with parallel edges of the

same width as the slot-faces to form ways or sliding supports on which the brackets c and d are held. The bracket c is expanded into a top having the horizontal arms e, on which the board f rests, which forms the bottom of the desk proper, c', which is held by bolts or screws, as shown. The bracket c has an inclined member or base c', provided with lips k, which project over the sides of said ways, and one of said lips is formed into rack-teeth l, which mesh into a pinion m, journaled in the member A. Said pinion is turned by a removable crank or wrench n, whereby the sliding members c' and d' may be moved up and down on their supporting-legs a, and from the lower end of c' rise curved brackets c², which are held together and to a web of said bracket by a bolt c³, each bracket resting on a fulcrum c⁴, thus forming a rigid foot-ing to resist horizontal vibration of the desk 30 above. The ends e' of said brackets are fastened to the board f. The bolts o of said sliding pieces pass through the slots a a and their nuts bind said inclined parts c' and d' firmly.

75 The seat-bracket d has an inclined member d', provided with a rack l, pinion m, and fastening-bolt o, like the bracket c; but the upper end d² thereof extends forward, is expanded, and provided with a longitudinal slot d³, in which plays a bolt d⁴, fixed into the back d⁵, whereby said back has a vertical adjustment toward and from the seat d⁶. The lower end of the inclined holder d is turned upward into two curved arms g, their ends 80 holding a pintle-rod g', on which turn lugs g², forming the ends of a seat-piece g³, carrying the seat d⁶. Said seat-piece has a central rib extending both forward and back from said rod g' and continues rearwardly, forming a tailpiece or spur h', which is caught under a bracket or spur h² on the part d⁶, whereby the inclination of the seat is adjusted either fixedly or variably when said spur is made adjustable, as indicated in 85 broken outlines. By spreading said arms g, as shown, from about three inches to ten inches, more or less, the seat is easily held in a very rigid position and thereby noiseless manner. When desirable, said seat may be 90

so nearly balanced as to be made to rise into the vertical position by a very slight tilt. Said end is attained by either weighting said spur h' or by a spring h on the rod g' and seat 5 and arms, as shown, just strong enough to produce said condition. The front and rear slot-faces b and b' approach at their upper ends from the base about a quarter of an inch more or less. When, therefore, it is desired 10 to adjust a seat or desk, it is raised to its upper limit and held by the nut of the bolt o , from which by releasing said nut slowly its bracket will drop by short intervals under such release until the right point is reached 15 and the nut reversed and firmly set. Said racks l and their pinions are not indispensable, because the parts may be lifted by hand to their upper limits of adjustment.

What I claim is—

20 1. The combination with longitudinally-slotted and oppositely-inclined floor members, of a reciprocable desk-holding element and means to hold it, regulably, in one of said slots and brackets secured to said reciproca-

ble element provided with flat ends tangent 25 to the desk-bottom, substantially as specified.

2. The combination with a longitudinally-slotted floor member, of a desk-holder on 30 said member provided with fixed desk-holding element, means to adjust said holder, and removable brackets thereon, terminating in the plane of the desk-bottom, substantially as specified.

3. The combination with an inclined bifurcated seat-bracket, an inclined floor member thereto and said bracket provided at the 35 ends of said members with hinge elements, of a tailed seat-support having counterpart hinge elements provided with a single central tailpiece, means for connecting said hinge elements, and a stop for said tail, substantially as specified.
